Patented Oct. 30, 1973

228,837

RECLINING CHAIR

Ronald W. Hari, El Cerrito, Calif.
(940 E. Napa St., Sonoma, Calif. 95476)

Filed July 28, 1971, Ser. No. 167,076

Term of patent 14 years

Int. Cl. D6—02

U.S. Cl. D6—75

F i g. 4F i g. 5

FIG. 1 is an isometric view of a reclining chair showing my new design;

FIG. 2 is a side view (both sides are the same);

FIG. 3 is a front view;

FIG. 4 is a top view; and

FIG. 5 is a back view.

I claim:

The ornamental design for a reclining chair, as shown.
